UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

WINDING-MACHINE.

1,179,459.

Specification of Letters Patent.

Patented Apr. 18, 1916.

Application filed January 14, 1915. Serial No. 2,149.

To all whom it may concern:

Be it known that I, EPPA H. RYON, a citizen of the United States, residing at Waltham, in the county of Middlesex and 5 State of Massachusetts, have invented a new and useful Winding-Machine, of which the following is a specification.

This invention relates to a winding machine and particularly to improved yarn 10 guiding devices for such a machine.

In the operation of the so-called "feeler" looms it has been found desirable to wind a certain amount of yarn upon the weft carrier at a given point in its length before 15 the usual traverse winding is commenced. This preliminary winding, or "bunch" as it is called, affords a reserve supply of yarn for use between the indication of the feeler and the insertion of a fresh weft carrier.

20 It is the principal object of my invention to provide improved devices for guiding the yarn in a winding machine by the use of which a preliminary bunch of yarn may be wound upon the weft carrier.

25 It is a further object of my invention to provide means for automatically introducing the regular traverse wind after a pre-determined amount of yarn has been placed upon the carrier.

30 In the preferred embodiment of my invention I provide an auxiliary guide for the yarn, manually-adjustable devices for retaining said guide in operative position, and automatic yarn-operated devices for 35 rendering said auxiliary guide inoperative.

With these objects in view my invention relates to certain devices, arrangements and combinations of parts which will be hereinafter described and more particularly 40 pointed out in the appended claims.

Two forms of my invention are shown in the drawings, in which—

Figure 1 is a plan view of a portion of a winding machine with my improved yarn 45 guiding devices applied thereto; Fig. 2 is a horizontal sectional view taken along the line 2—2 in Fig. 4; Fig. 3 is a plan view of certain of the parts shown in Fig. 1 but showing the auxiliary guide in inoperative 50 position; Fig. 4 is a left-hand elevation of certain of the parts shown in Fig. 1; Fig. 5 is a horizontal sectional view similar to Fig. 2 but showing the latch in a different

position; Figs. 6 and 7 are plan views of a modified form of my invention with the 55 parts in different positions; and Fig. 8 is a rear elevation of the modified form, with the parts in the position shown in Fig. 6.

My invention as shown is applied to a winding machine of the type shown in my 60 prior Patent No. 1,061,013 issued May 6, 1913.

In Fig. 1 I have shown the rotating spindle 10, the fixed longitudinal guide rods 11 and 12, and the trumpet carrier 13 slidable 65 on said rods and supporting the trumpet 13^a. Suitable provision is made upon the spindle 10 for driving the bobbin or weft carrier 14. This weft carrier may be of any suitable type and as shown in the drawing 70 comprises a butt 15 having parallel cut-away portions 16 on each side thereof and also provided with grooves 17 cut into its conical portion in a plane parallel to the flat sides of the cut-away portions 16. The 75 weft carrier is also provided with a groove 18 adjacent the butt 15, within which a reserve supply of yarn may be wound before the usual traverse winding is commenced. As yarn is run off in the shuttle, the yarn 80 covering the grooves 17 will eventually be exhausted, permitting the feeler to enter one of the grooves and thereby indicate the filling change. One or more picks of filling 85 must necessarily be inserted in the cloth before a fresh weft carrier can be placed in the shuttle and the yarn preliminarily wound in the groove 18 furnishes the filling necessary for this purpose.

In a winding machine of the type shown, 90 the spindle rotates in a fixed longitudinal position and the trumpet and trumpet carrier move toward the tip of the weft carrier as increasing amounts of yarn are wound upon it.

The weft carrier 14 and trumpet 13^a are shown in each of the figures in the drawings in the position which they occupy when the winding upon a newly inserted weft carrier is about to begin. The usual traverse 100 yarn guide is shown at 20, this guide having a reciprocating motion communicated to it by any suitable mechanism (not shown). For a full description of one form of such mechanism, reference is made to my prior 105 patent.

While winding the bunch I use an auxiliary yarn guide which in Fig. 1 comprises a U-shaped rod 21 slideable in a projection 22 formed upon the outer wall of the trumpet. One end of the rod 21 is provided with a transverse head 23 and a coil spring 24 encircles one leg of the rod and normally forces the rod to the right until the head 23 engages the side of the projection 22. A latch 25 (Fig. 4) is pivoted to an ear 26 upon the lower outer side of the trumpet and the upper end of the latch 25 is movable into position to engage the head 23 upon the rod 21, retaining the same in the position shown in Fig. 1. When the rod 21 is in this position the end 28 of the rod 21 extends beyond the projection 22 and engages a second lug or projection 29, thereby forming a passage through which the yarn is guided to the weft carrier as also shown in Fig. 1. A spring 27 (Fig. 8) may be added to move the latch 25 toward operative position. The trumpet 13^a has a vertical slot 13^b positioned adjacent the groove 18 in the weft carrier when the winding of the carrier is about to commence and the latch 25 is provided with a projection 30 positioned to extend through the slot 13^b when the latch is in operative position. In the operation of this form of my invention, the yarn is led through the traverse guide 20 and around the end 28 of the auxiliary guide rod 21 and the rod is then moved to the left until the latch 25 can be inserted between the head 23 and the projection 22. The machine may then be set in operation and the yarn will be guided by the auxiliary guide into the groove 18, regardless of the reciprocating movements of the traverse guide 20. When the groove 18 is filled with yarn, as shown in Fig. 5, the latch 25 will be forced rearwardly until it is disengaged from head 23, when the spring 28 will move the rod 21 to the right as shown in Fig. 3, thus releasing the yarn from the control of the auxiliary guide, and permitting the usual traverse wind under the control of the traverse guide 20.

In the modified form shown in Figs. 6, 7 and 8, an auxiliary guide 40 is pivoted to the trumpet at 41 and is provided with a spring 42 effective to move the guide to the inoperative position shown in Fig. 7. The guide 40 also carries a rearwardly extending lug 43 positioned for engagement by the upper end of a latch 25^a by which it will be retained in the operative position shown in Fig. 6. When the groove 18 is filled with yarn the latch will be forced rearwardly and the spring 42 will immediately move the guide 40 to its inoperative position.

Having thus described my invention it will be evident that other changes and modifications can be made therein by those skilled in the art without departing from

the spirit and scope thereof as set forth in the claims and I do not wish to be otherwise limited to the details herein disclosed, but

What I do claim is:—

1. In a winding machine, in combination, a rotating spindle driving a weft carrier, a yarn guide having a reciprocating motion longitudinally of said spindle and carrier, an auxiliary yarn guide mounted adjacent said spindle for winding a preliminary bunch of yarn on said weft carrier, and means to render said auxiliary guide operative and inoperative, said means being directly engaged by the bunch of yarn formed on the weft carrier and being actuated thereby to render said auxiliary guide inoperative when the bunch of yarn attains a predetermined size. 70

2. In a winding machine, in combination, a rotating spindle driving a weft carrier, a yarn guide having a reciprocating motion longitudinally of said spindle and carrier, an auxiliary yarn guide mounted adjacent said spindle for winding a preliminary bunch of yarn on said weft carrier, and means to render said auxiliary guide operative and inoperative, said means being directly controlled by the diameter of the bunch of yarn wound upon the weft carrier. 85

3. In a winding machine, in combination, a rotating spindle driving a weft carrier, a yarn guide having a reciprocating motion longitudinally of said spindle and carrier, an auxiliary yarn guide mounted adjacent said spindle for winding a preliminary bunch of yarn on said weft carrier, means to render said auxiliary guide operative, and additional means to render said guide inoperative, said latter means becoming effective only when a bunch of yarn of predetermined diameter has been placed on the bobbin and entirely independently of the number of revolutions of the weft carrier supporting spindle. 95 100

4. In a winding machine, in combination, a rotating spindle driving a weft carrier, a trumpet, a yarn guide having a reciprocating motion longitudinally of said spindle and carrier, an auxiliary yarn guide for winding a preliminary bunch of yarn on said weft carrier, a spring to move said auxiliary guide to inoperative position, and a latch to retain said guide in operative position, said latch directly engaging the bunch of yarn on the weft carrier and being rendered inoperative by the completion of a bunch of yarn of predetermined diameter. 110 115 120

5. In a winding machine, in combination, a rotating spindle driving a weft carrier, a trumpet, a yarn guide having a reciprocating motion longitudinally of said spindle and carrier, an auxiliary yarn guide, a spring to move said auxiliary guide to inoperative position, and a latch to retain said auxiliary guide in operative position, said 125 130

latch having a portion projecting through a slot in the side of the trumpet in position to be engaged and pressed outwardly by a bunch of yarn wound upon the weft carrier.

5 6. In a winding machine, in combination, a rotating spindle driving a weft carrier, a trumpet, a yarn guide having a reciprocating motion longitudinally of said spindle and carrier, an auxiliary yarn guide, a

10 spring to move said guide to inoperative position, and a latch to retain said guide in operative position, said carrier having a circumferential groove, said trumpet having a slot positioned adjacent said groove when

15 the carrier is freshly inserted, and said latch having a projection extending through said slot into position to be engaged and forced outward by the yarn wound in the groove of the carrier, outward movement of said

20 latch permitting movement of said auxiliary guide to inoperative position.

7. In a winding machine, in combination, a rotating spindle driving a weft carrier, a trumpet, said spindle and trumpet being

relatively movable longitudinally, a yarn 25 guide having a predetermined traverse relative to said trumpet, a second yarn guide having a fixed operative position relative to said trumpet, and means to render said second yarn guide automatically inoperative. 30

8. In a winding machine, in combination, a rotating spindle driving a weft carrier, a trumpet, said spindle and trumpet being relatively movable longitudinally, a yarn 35 guide having a predetermined traverse relative to said trumpet, a second yarn guide mounted on said trumpet, means to hold said second yarn guide in operative position on said trumpet, and means to render said second yarn guide automatically inoperative. 40

In testimony whereof I have hereunto set my hand, in the presence of two subscribing witnesses.

EPPA H. RYON.
